UNITED STATES PATENT OFFICE

SAMUEL C. BLOOM, OF CHICAGO, ILLINOIS

SPRAY NOZZLE

Application filed May 13, 1927. Serial No. 191,156.

This invention relates to improvements in spray nozzles and more especially to such a nozzle particularly adapted for producing a spray, or mist, of a cooling fluid, such as, for example, brine.

Spray nozzles of the character described are frequently used in connection with refrigerating apparatus for producing a spray, or mist, of cooled brine to cool air.

10 One of the features of my invention is the production of such a nozzle that is reliable and efficient in operation. My improved nozzle will produce an exceedingly fine mist, or spray, and diffuse the same through a maximum space.

15 My improved nozzle is also constructed so that it can be easily and readily cleaned. To this end, it is so constructed that all accumulations of dirt will remain in the removable cap, thus permitting the cap to be taken off the nozzle and easily cleaned in an accessible position. This provision permitting dirt to accumulate in the cap, instead of the base of the nozzle, also prevents any of such dirt from 20 falling back in the supply pipe during the cleaning operation. In many cases, also, the cleaning may be performed without taking off the nozzle at all, or even removing the cap.

25 My improved nozzle is also so constructed that the liability of clogging from particles of dirt is reduced to a minimum. Other features and advantages of my invention will appear more fully as I proceed with my specification.

30 In that form of device embodying the features of my invention shown in the accompanying drawings,

Fig. 1 is a top plan view of my improved nozzle; Fig. 2 is a view partly in side elevation and partly in section of the helical groove core forming part of the nozzle; Fig. 3 is a vertical sectional view of the complete nozzle; and Fig. 4 is a view similar to Fig. 3 showing the core retracted a short distance for the 35 cleaning operation.

40 As shown in the drawings, the nozzle comprises a base part 10 here shown as a threaded nipple, a cap 11 with a tapered chamber 11^a inside, and a correspondingly tapered helical 45 grooved core 12 lying inside of the cap 11.

The base 10 is preferably provided with a shoulder 10^a and the lower end of the cap 11 is provided with internal threads 11^c for mounting it on the base. When thus mounted, its lower end is preferably in contact with the shoulder 10^a in order to produce a liquid-tight joint. 10^b indicates a water-supply outlet in the base part and the outer end of this water-supply outlet is enlarged on a taper, as indicated by 10^c, so that its diameter at the 55 end is substantially equal to the diameter of the large end of the tapered chamber 11^a in the cap 11.

The outer or small end of the tapered chamber 11^a is provided with a spray aperture 11^b. 60

As stated, 12 indicates a tapered core adapted to lie in the tapered chamber 11^a of the cap 11. This core is provided with a double helical groove 12^a to divide the passing liquid into two streams and give them 65 both a rotary motion to assist in forming the spray, or mist, issuing from the spray aperture 11^b. It is to be particularly noted that the grooves 12^a are substantially round in cross section, as shown in Fig. 2, instead of 70 being V-shaped, or flattened, as in the case of most ordinary threads. That is, the bottom of each of the grooves 12^a is rounded, as indicated by 12^b (see Fig. 2). It will be seen that 75 by forming these grooves substantially round in cross section, the liability of clogging is reduced to a minimum. That is, a groove which is substantially round in cross section will pass larger particles of dirt or obstructions per unit of area than a groove of any 80 other shape. Such a groove also interposes less friction, or resistance, to the passage of fluid per unit of volume than a groove of any other shape, thus increasing the efficiency of 85 the nozzle.

90 It is to be noted that the core 12 is somewhat shorter than the chamber 11^a and when it is in position its forward end lies some distance from the spray aperture 11^b, thus leaving in the smaller end of the cap 11 a mixing 95 chamber, as indicated by 11^d. As a matter of fact, this mixing chamber referred to as 11^d constitutes the forward or smaller end of the entire tapered chamber 11^a of the cap. The mixing chamber 11^d permits the two streams 100

upon leaving the core 12 to thoroughly mix and flatten out before issuing from the aperture 11^b, thus making a uniformly dense spray cone.

5 The larger end of the core 12 also lies some distance from the large end of the cap 11, thus forming a dirt chamber 11^a which constitutes in fact the large end of the tapered chamber 11^a of the cap. It will be 10 seen that any obstruction and particles of dirt that cannot pass the core 12 will accumulate in this dirt chamber 11^a, and it is to be particularly noted that this dirt chamber 11^a is in the cap so that all such 15 accumulations of dirt and foreign material will lodge in the cap itself and not in the base part 10. Consequently, when the nozzle is to be cleaned, the cap may be removed and the accumulation of dirt will 20 thus be taken away from the base in the cap, from which it can be easily cleaned out. By thus removing the dirt with the cap, all likelihood of the dirt falling back in the water-outlet 10^b is eliminated. In connection with this cleaning of the nozzle, it is 25 to be particularly noted that the cleaning just referred to by removal of the cap is not always necessary. In many cases, if the accumulation of dirt is not too great, the 30 nozzle may be cleaned without removing the cap at all. This is accomplished by simply retracting or pushing back the core 12 in the nozzle, as shown in Fig. 4. This may be done by forcing the point of a nail, or 35 other small instrument, into the aperture 11^b to engage the core and push it back while a small stream of liquid is flowing. Such movement of the core ordinarily will 40 loosen up dirt and permit it to issue from the aperture 11^b. When the full pressure of liquid is again turned on, it forces the core back into place in the cap as shown in Fig. 4. It is to be noted that the outer end of 45 the water outlet 10^b is somewhat enlarged, as indicated at 10^a, so that at the extreme end its diameter is substantially the same as the diameter of the larger end of the chamber 11^a. This construction permits the core 12 to be retracted down into the base, 50 as shown in Fig. 4, thus further assisting in the cleaning operation just referred to. It is to be noted also that the enlargement 55 10^a of the water outlet is tapered so that, with the exception of the core 12, there are no shoulders, or abrupt edges, opposed against the travel of liquid through the nozzle.

60 The foregoing detailed description has been given for clearness of understanding only, and no unnecessary limitations should be understood therefrom, but the appended claims should be construed as broadly as permissible, in view of the prior art.

65 As stated above, the enlargement 10^a of

the water outlet is tapered. By means of this construction, the core 12 may be pressed into this tapered opening and jammed there, so that the cap 11 may be removed without danger of losing the core 12. Such jamming 70 just referred to may be accomplished whether the nozzle is pointing horizontally or in a downward direction. By being able to push the core back into this tapered opening in the base, the removal and cleaning of the cap of the nozzle is greatly facilitated.

75 What I regard as new, and desire to secure by Letters Patent, is:

1. A spray nozzle of the character described comprising; a base part with a water supply outlet; a cap with a tapered chamber secured to the base part, the large end of the chamber being adjacent the water supply outlet, and the small end provided with a spray aperture; and a correspondingly tapered core with a helical groove on its outer surface lying in the tapered chamber in the cap, the inner end of said core being spaced from the outer end of the base part, the outer end of the water supply outlet in the base being enlarged on a taper to a diameter substantially equal to the diameter of the large end of the tapered chamber in the cap and the inner end of said water supply outlet having a diameter smaller than the larger diameter of the tapered core, whereby the core may be moved from the chamber in the cap into the tapered outer end of the water supply outlet in the base.

80 85 90 95 100 105 110 115 120 125 130

2. A spray nozzle as claimed in claim 1, in which the degree of taper of the outer end of the water supply outlet in the base is such that when the core is moved thereto, it may be jammed in said outlet.

In witness whereof, I have hereunto set my hand this 11th day of May, 1927.

SAMUEL C. BLOOM.
